[57] **CLAIM**

The ornamental design for combined handset telephone and stand therefor, as shown and described.

DESCRIPTION

FIG. 1 is a left side, top and rear end perspective view of a combined handset telephone and stand therefor showing my new design in cradled relationship;

FIG. 2 is a left side elevational view thereof, the side opposite being a substantially a mirror image;

FIG. 3 is a bracket associated perspective view of the left, top, and rear end of the stand and a bottom plan view of the handset telephone, shown spaced apart for clarity of illustration;

FIG. 4 is a similar bracket associated perspective view of the bottom and rear end of the handset telephone and a rear end, top, and right side of the stand, shown spaced apart;

FIG. 5 is a left side, top and rear end of a second embodiment thereof shown in cradled relationship;

FIG. 6 is a left side elevational view thereof, the side opposite being substantially a mirror image thereof;

FIG. 7 is a bracket associated perspective view of the left side, top and rear end of the stand and a bottom plan view of the handset telephone thereof shown spaced apart for clarity of illustration;

FIG. 8 is a similar bracket associated perspective view of the left side, bottom, and rear end of the handset telephone and a rear end, top and right side of the stand; and

FIG. 9 is a bottom plan view of the stand.

The bottom of the base of the first embodiment is plain
